UNITED STATES PATENT OFFICE.

JAMES H. GAULT, OF PHILADELPHIA, PENNSYLVANIA.

DESIGN FOR A POCKET-PIECE.

No. 37,574.

Specification for Design.

Patented Oct. 24, 1905.

Application filed June 15, 1905. Serial No. 265,457. Term of patent 14 years.

To all whom it may concern:

Be it known that I, JAMES H. GAULT, a citizen of the United States, residing at Philadelphia, county of Philadelphia, and State of Pennsylvania, have invented a new, original, and ornamental Design for a Pocket-Piece, reference being had to the accompanying drawing for an illustration of the same.

The drawing represents the two faces of a pocket-piece embodying my design.

I claim—

The ornamental design for a pocket-piece, as shown.

JAMES H. GAULT.
